UNITED STATES PATENT OFFICE.

HOWARD EARL SIMMONS AND PAUL R. SIMMONS, OF HUNTINGTON, INDIANA.

DESIGN FOR A PNEUMATIC METAL WHEEL.

•54,564.

Specification for Design.

Patented Mar. 2, 1920.

Application filed September 6, 1919. Serial No. 322,203. Term of patent 14 years.

To all whom it may concern:

Be it known that we, HOWARD E. SIMMONS and PAUL R. SIMMONS, both citizens of the United States, and residents of Huntington, in the county of Huntington and State of Indiana, have invented a new, original, and ornamental Design for a Pneumatic Metal Wheel, of which the following is a specification.

Reference is to be had to the accompanying drawing, in which—

Figure 1 is a side elevation of a wheel showing the improved design, and Fig. 2 is an edge view thereof.

We claim—

The ornamental design for a pneumatic metal wheel, as shown.

HOWARD EARL SIMMONS.
PAUL R. SIMMONS.
